COMBINATION CABANA AND SOLARIUM THEREFOR

Mike Tecton, 5101 45th St. NW., Washington, D.C.

Filed Mar. 16, 1965, Ser. No. 84,288

Term of patent 14 years

(Cl. D83—1)

FIG. 1

FIG. 2

FIG. 3

FIG. 4

FIG. 1 is a perspective view of a combination cabana and solarium therefor embodying my new design;

FIG. 2 is a right side elevational view thereof;

FIG. 3 is a rear elevational view thereof;

FIG. 4 is a top plan view thereof.

I claim:

The ornamental design for a combination cabana and solarium therefor, substantially as shown.
